UNITED STATES PATENT OFFICE.

JEREMIAH J. SCANNELL, OF DETROIT, MICHIGAN.

PORTABLE SHOWER-BATH FIXTURE.

Application filed July 15, 1922. Serial No. 575,369.

To all whom it may concern:

Be it known that I, JEREMIAH J. SCANNELL, a citizen of the United States, residing at Detroit, in the county of Wayne and 5 State of Michigan, have invented a new and useful Portable Shower-Bath Fixture, of which the following is a specification.

This invention relates to portable shower bath fixtures, and more particularly to 10 shower bath fixtures adapted for quick detachable connection to a bath tub.

It is the object of the invention to provide a novel means for quick detachably mounting in proximity to a bath tub an upright 15 water pipe providing a supply connection from the faucet of the tub to a spray head carried by the upper portion of said pipe.

The use of a flexible connection from the faucet to said pipe, permitting rotative adjustment of the latter to position the spray 20 head centrally of the hub, is a further feature of the invention.

A preferred embodiment of the invention is hereinafter described and is illustrated 25 in the accompanying drawing, wherein,

Fig. 1 is a view in side elevation of the improved fixture, showing in cross-section the tub to which it is applied.

Fig. 2 is a front elevation view of the 30 same.

Fig. 3 is an enlarged view in partial section of the lower portion of the fixture.

In these views, the reference character 1 designates an ordinary bath-tub having the 35 usual marginal depending flange 2, and having a faucet 3. The shower bath attachment comprises an upright pipe 4 mounted exteriorly of the tub adjacent the latter and having just above the tub edge an inlet 5 40 for connection with said faucet, said pipe being extended a considerable distance above the tub and having adjacent its top the lateral outlet pipe 6 terminally provided with the spray nozzle head 7. Above 45 said outlet and below said inlet, the pipe 4 is closed by suitable plugs 8. Thus the portion of said pipe below said inlet functions merely as a support. 9 is a short length of hose having terminal mouthpieces 50 10 formed preferably of rubber so that they may be elastically engaged with the faucet 3 and inlet 5. 11 is a ring secured to the top of the pipe 4 above the spray head 7 to suspend a curtain (not shown), which will

confine the spray jets from said head and insure delivery of said jets to the tub.

Describing now the mounting of the pipe 4, 12 is a flanged socket for receiving the foot of the pipe 4, said socket being secured to the bath room floor by screws 13 or the like. Said pipe rests freely in the socket 12, which latter is so located that the pipe may extend vertically therefrom in close proximity to the flange 2. 14 is a set collar adapted to be retained by a clamping screw 15 in any desired position of rotative or longitudinal adjustment upon the pipe 4. At a point diametrically opposite said set screw a pair of divergent and upwardly inclined prongs 16 are integrally formed 70 upon said collar for the purpose of engaging the inner face of the depending flange 2 as clearly shown in Fig. 1. Thus said prongs are adapted to co-act with the socket 12 to securely maintain the shower-bath fixture in its proper upright position. The engagement of said prongs with the top portion of the flange 2 will prevent any swinging of the pipe 4 parallel to the tub, and the position of the flange engaged between said prongs and the pipe holds the latter from swinging to or from the tub. In 75 positioning the attachment, the collar 14 is originally adjusted to a point below the flange 2 and after the pipe 4 has been seated 80 in the socket 12 and disposed vertically adjacent the tub, the collar 14 is slid up to engage the prongs 16 behind the flange 2, and the set screw 15 is tightened.

It is to be noted that the pipe 4 is rotatable in the socket 12 and may be rotatably adjusted with respect to the collar 14. Thus the discharge pipe 6 may be extended more or less toward the center of the tub so that the user of the device is not 90 limited to a position opposite the pipe 4 at the head of the tub. After use, the described attachment may, if desired, be readily removed by disengaging the collar to permit withdrawal of the upright from the 95 floor socket.

What I claim is:

1. A shower bath attachment for a bath-tub having a marginal depending flange, comprising a pipe carrying a spray head 105 adjacent one end and having an inlet, a support carried by said pipe, a floor socket engageable by said support, means for con-

necting the inlet of said pipe to a faucet of the tub, and means longitudinally adjustable upon said support engageable with the depending flange of the tub to co-act 5 with said socket to hold said pipe upright.

2. A shower bath attachment for a bathtub having a marginal depending flange, comprising a pipe carrying a spray head adjacent one end and having an inlet, a 10 support carried by said pipe, a floor socket engageable by said support, means for connecting the inlet of said pipe to a faucet of the tub, a collar longitudinally adjustable upon said pipe, and means upwardly projecting from said collar for engagement be- 15

hind said flange at points sufficiently spaced longitudinally of the flange to prevent swinging of the pipe parallel to the tub.

3. A shower bath attachment for a bathtub comprising a pipe carrying a spray head adjacent one end and having an inlet, and a supporting portion closed off from said inlet, a floor socket engageable terminally by said supporting portion, and means for securing said supporting portion rigidly 20 to a margin of the tub, 25

In testimony whereof I sign this specification.

JEREMIAH J. SCANNELL.
